(57) **CLAIM**

The ornamental design for a tool, as shown and described.

DESCRIPTION

FIG. 1 is a front perspective view of a tool according to the invention;

FIG. 2 is a rear perspective view of a tool according to the invention;

FIG. 3 is a front view of a tool according to the invention;

FIG. 4 is a rear view of a tool according to the invention;

FIG. 5 is a front side view of a tool according to the invention;

FIG. 6 is a rear side view of a tool according to the invention;

FIG. 7 is a top end view of a tool according to the invention;

FIG. 8 is a bottom end view of a tool according to the invention;

FIG. 9 is a front perspective view of a tool according to the invention, with the tip of the tool shown uninstalled;

FIG. 10 rear perspective view of a tool according to the invention, with the tip of the tool shown uninstalled;

FIG. 11 is a front view of a tool according to the invention, with the tip of the tool shown uninstalled;

FIG. 12 is a bottom view of a tool according to the invention, with the tip of the tool shown uninstalled;

FIG. 13 is a front side view of a tool according to the invention, with the tip of the tool shown uninstalled;

FIG. 14 is a rear side view of a tool according to the invention, with the tip of the tool shown uninstalled;

FIG. 15 is a top end view of a tool according to the invention, with the tip of the tool shown uninstalled; and,

FIG. 16 is a bottom end view of a tool according to the invention, with the tip of the tool shown uninstalled.

The tool is shown with a symbolic break in its handle. The appearance of any portion of the article between the break lines forms no part of the claimed design.

1 Claim, 11 Drawing Sheets
